UNITED STATES PATENT OFFICE.

WILBUR N. SHELTON, OF BOSTON, MASSACHUSETTS.

ADHESIVE REPAIR DEVICE.

941,047.

Specification of Letters Patent. Patented Nov. 23, 1909.

Application filed March 18, 1908. Serial No. 421,895.

To all whom it may concern:

Be it known that I, WILBUR N. SHELTON, a citizen of the United States, and a resident of Boston, in the county of Suffolk and State of Massachusetts, have invented an Improvement in Adhesive Repair Devices, of which the following description, in connection with the accompanying drawings, is a specification, like figures on the drawings 10 representing like parts.

This invention pertains to an adhesive device used for patching or repairing fabrics or the like.

One object of the invention is to provide 15 an adhesive patch which shall be convenient in use and shall adhere strongly and permanently in its desired position.

The character of the invention may be best understood by reference to the accompanying drawings which illustrate various forms 20 in which the invention may be embodied.

In the drawings: Figure 1 shows a piece 25 of fabric or the like, having a substantially circular hole therein patched by an adhesive device embodying this invention; Fig. 2 shows a piece of fabric or the like having a crescent shaped hole appropriately patched; Fig. 3 is a transverse section on a line 4—4 of Fig. 1, illustrating the filling means 30 occupying the space in a hole (the scale of Fig. 3 is considerably exaggerated, for the sake of clearness); Fig. 4 illustrates a use of a formed adhesive patch or repairing device; and Fig. 5 a detail section on the line 6—6 35 of Fig. 4.

Referring now to the drawings, my novel patch comprises a fabric member 5, of a material preferably similar to that which is to be repaired and upon this fabric member is 40 placed a coating or layer of an adhesive agent such as a gutta-percha cement, or any other cement that requires heat or other special treatment to render it temporarily conditioned for uniting fabrics—the union becoming set and permanent as the cement 45 cools or resumes its final condition. Such a cement may be formed from gutta-percha, cut by bicarbonate of soda or other appropriate element, the same being applied to the 50 face of the patch material by spreading or calendering. Such a patch may be readily applied to a round hole 6, a crescent shaped hole 7, or a hole of any other shape, or in various other connections which will appear to 55 those skilled in the art, by simply applying

the adhesive patch to the article to be repaired and preferably heating and pressing the two firmly together, until the adhesive incorporates itself securely with the surface of the material to be patched or otherwise 60 repaired. The patch member may be fashioned to a convex or concave form, and supplied as in other cases with a suitable adhesive. For example, Fig. 4 illustrates a manner of repairing a hole in the heel of a 65 sock or stocking. The hole 9, located at the convex part of the heel, would be difficult to repair by means of a flat patch. Accordingly, a patch 10 of fashioned fabric or the like, shaped to appropriate conformation, 70 may be placed upon or shaped over a suitable form such as the heel of a last, or the like, with its adhesive surface outward; and then the sock to be repaired may be drawn over the patch-bearing form or any other 75 shaping element and the two ironed firmly together, preferably with heat.

With any such patch as has been described, whether flat or fashioned to convex or concave form, there is employed filling means 80 12, as shown in Fig. 3, and the patch 5 may be applied either before or after the filling material 12 has been assembled in the hole to be repaired in the material 14. To suit this purpose, the entire lower surface of the 85 patch 5 in Fig. 3 may be covered with adhesive, serving to hold the filling material 12 in place. This material 12 may well be exactly like the material 14, so that if snugly fitted in the hole and skillfully patched and 90 ironed the hole will be practically indistinguishable.

If desired, the patch member 5 may be reduced in thickness near its edges, as shown in Fig. 3, and this may be effected in any 95 practicable manner as by heavily compressing or scarfing the patch material near its periphery, causing it to taper from within outwardly. By this means such thickness as is added by the presence of the patch 100 may be graduated so as to relieve the patched or repaired areas of bunches.

As illustrated in Fig. 5, the fashioned filling material 16, similar to the filling means 12 of Fig. 3, may be employed to fill 105 out a hole in material having a concave or convex conformation. In such case the patch 10 may desirably taper down to a thin edge as shown.

This invention has many desirable and 110

valuable advantages, the repairing device or patch, such as contemplated, being applied very quickly with facility.

The embodiments of the invention hereinbefore described are intended merely for purposes of illustration and the invention is not to be construed as essentially limited thereto.

Claims—

- 10 1. As an article of manufacture, a patch comprising in combination a fabric member fashioned to convex form and having an adhesive thereon to engage and become incorporated with material encircling a hole 15 to be patched; and a filler adhering to the fashioned fabric member and also fashioned to the form thereof, said filler being adapted to fill out the hole in the material to be repaired.
- 20 2. An article of manufacture comprising in combination a fabric member fashioned to convex form and having its periphery of reduced thickness; a layer of adhesive material on a face of the fashioned member to

unite the latter with material having a hole 25 to be patched; and a filler of the same material as that to be patched, united to the fashioned member and itself fashioned to the form thereof, said filler being suitably proportioned and shaped to fill the hole in 30 said material to be repaired.

3. An article of manufacture consisting of a patch member having a fabric body with a layer of adhesive thereon, and a filling member, smaller than said patch and united 35 to the latter by the adhesive, the patch member covering the entire face of the filling member, leaving a margin of adhesive patch member for securing the article in position with the filling member filling a hole to be 40 patched.

In testimony whereof, I have signed my name to this specification, in the presence of two subscribing witnesses.

WILBUR N. SHELTON.
